METHOD AND APPARATUS FOR TAKING SOUNDINGS

Application filed September 23, 1927, Serial No. 221,588, and in France October 28, 1926.

The present invention has for an object the utilization of a glow discharge lamp as a relay in apparatus for sounding or signaling by elastic waves.

5 The glow discharge lamps employed have the following necessary properties:

The lamp being extinguished, when the voltage impressed thereupon is gradually increased, a luminous discharge is suddenly

10 produced for a well determined value of said voltage, which will hereinafter be referred to as the "upper critical voltage". The lamp being lighted, when the voltage impressed thereupon is gradually reduced, the luminous

15 discharge suddenly ceases for another well determined value of said voltage, which is lower than the value above referred to and which will be called "lower critical voltage".

If the lamp is connected to an auxiliary 20 source of potential which impresses thereupon a voltage slightly lower than the upper critical value, the lamp is rendered extremely sensitive to lighting.

In fact, a very weak increase in voltage, 25 produced by the phenomenon to be detected, is sufficient for releasing an electric discharge so that it will be possible to utilize either the illumination produced by said discharge or the relatively considerable current which 30 flows through it by means of special devices for the desired result as will be subsequently pointed out.

The lamp may also be sensitized to the 35 point of extinguishment, or lower critical value, that is, the lamp being lighted, the auxiliary source of potential is so regulated as to impress upon the lamp a voltage comprised between the upper critical value and the lower critical value. Any suitable temporary fall 40 in the supply voltage brings the voltage of the lamp to a value less than the lower critical value, whereby extinction is produced.

The description which follows, with regard 45 to the annexed drawings, given by way of example, explains very well the manner in which the invention can be carried into practice.

Fig. 1 represents the electric diagram of a 50 sounding apparatus in which the variations

of illumination of a lamp as above described are utilized.

Fig. 1a is a modification of a part of Fig. 1.

Fig. 2 represents the diagram of an optical arrangement of such a sounding apparatus. 55

Fig. 3 is a side view.

Figs. 4 and 5 represent modifications in the mode of operation of the lamp.

Fig. 6 represents the way in which a low voltage glow discharge tube having a plurality of electrodes is utilized. 60

Fig. 7 represents an arrangement utilizing the relay effect of the discharge current in a sounding apparatus or great depth sounder with an indicator. 65

Fig. 1 shows a supersonic sounder through which, in a well known manner, a signal is emitted and the echo thereof received.

Within the casing 1 is a damped waves high-frequency emitting apparatus, of a 70 known type, fed by the direct current source 2'.

2 is a piezo-electric condenser for emission and reception of ultra-audible waves, having one face in contact with the sea-water. It is 75 supplied with electrical energy by the high-frequency emitting apparatus disposed within the casing 1 and it projects into the water a high frequency compressional wave. The latter apparatus is reversible. When compressional waves resulting from the echo strike the condenser 2, the latter generates, in the electric circuits, a current having the same frequency as the signal, but of very small amplitude. 80

The condenser 2 is connected with an amplifier mounted within a casing 4. The output side of the amplifier 4 is connected by means of the transformer 5 to the circuit of the relay lamp 6. This relay lamp will consist in this case, for example, of a neon lamp of which the electrodes are covered with alkaline earth with a view to diminishing and more accurately determining the critical voltage. 85

The circuit of this relay neon lamp 6 comprises the transformer 5, a polarizing source 7 with a potentiometer 8 and a relay 9 of which the armature 10 is placed in circuit with the lamp while the winding 11 is con- 100

nected to the poles of the switch 3 by means of a condenser 12.

In this device, at the moment of emission of the signal, the neon lamp, lighted by a preceding echo, goes out and the echo corresponding to the signal relights it. The mode of operation of the system will be subsequently explained.

The mode of observing the lamp may be as follows: (Fig. 2).

10 The neon lamp is illustrated at 17. The luminous part comprises for example a cylinder 59 of which the horizontal axis is shown at 52-53. The arbor 54 turns at a constant speed and supports a mirror 55 and a lens 56 which turn about the shaft 54. The image 57 of the lamp is cast substantially in the plane of a circular graduated scale 58.

15 Fig. 3 shows the graduated scale 58. At 57 is the image of the lamp. The signal emitting device is so adjusted that the emission of a signal coincides always with the same position of the rotary optical system.

20 The image of the lamp is displaced about the scale, disappears at the position where the signal is emitted and reappears at the return of the echo for another position determining upon the graduated scale a dark sector following a light sector which dark sector is 25 proportional to the depth or distance to be measured.

The mode of operation of the arrangement is as follows:

25 The relay 9 is closed and the potentiometer 8 is adjusted on the battery 7 in such wise that the voltage at the terminals of the lamp will be slightly below the upper critical voltage and above the lower critical voltage.

30 The lamp is supposed to have been lighted 40 by a preceding echo. The relay 9 is closed, the switch 3 is open. The condenser 12 is charged by the source 2'. The charging current passes through the polarized relay 9 and the generator 1. The relay coil is wound in 45 such a direction that the charging current tends to close the relay and as this latter is already closed by magnetic polarization the charging current produces no action.

35 At the moment of emission, the switch 3 is closed, the condenser 12 is discharged in the 50 relay 9 connected to switch 3. The relay 9 breaks the circuit of the lamp and extinguishes said lamp. This circuit remains open as long as the condenser 12 remains 55 charged and the charging factor of the condenser is so designed that the time for discharging condenser 12 will be greater than the time of emission. In other words said condenser 12 is so chosen that 10 will close 60 the circuit of the lamp at a predetermined time after the signal is sent out.

When the condenser 12 is discharged the relay 9 closes but as the voltage furnished by the battery 7 and the potentiometer 8 is under the upper critical voltage of the lamp,

the latter is not relighted. When the echo returns it is amplified by the amplifier 4 and acts on the circuit of the relay lamp through the transformer 5.

70 The connections are such that they give an increase in voltage which lights the lamp 6 anew. There has been extinguishment of the lamp during the time between the emission of the signal and the return of the echo and the lamp will remain lighted until the 75 emission of the following signal.

78 The position of the obscure sector on the graduated scale will be determined by suitable inscriptions which will indicate the depth or distance sought.

80 If desired the operation may be reversed, that is to say, a luminous sector may be employed for determining the depth. In this case (Fig. 1^a) the voltage of the battery 7 will be regulated by 8 so that it is slightly 85 above the lower critical voltage and the phenomenon to be detected will produce a temporary decrease voltage. The circuit is then completed by a wire which connects one of the electrodes of 6 to the extremity of battery 90 7 through a resistance 7'. The operation is as follows:

85 The preceding echo puts out the lamp. During emission the relay opens, but instead of opening the lamp circuit the electrode remains connected to the extremity of the battery 7 and the lamp is lighted. When the relay closes the voltage on the lamp 6 is that of the potentiometer. When the echo arrives it produces a decrease of voltage which 95 extinguishes the lamp. In order that the device may give good results the decrease of voltage must last an appreciable time. This time will be diminished if instead of the 100 transformer 5a a resistance couple such as 105 shown in Fig. 4 be utilized and which will be described further on.

105 Any suitable apparatus may be utilized for causing the emission to take place simultaneously with the operation of the armature of relay 9. In particular, the principle of my invention would not be changed if the switch 3 and the relay 9 were controlled mechanically by the same device; for example, by two 110 cams fixed to the shaft of the motor which rotates the optical arrangement, above described.

115 This principle of inversion may be applied to the following figures without changing the principle of the invention.

120 Instead of producing an extinguishment of the lamp at the time of the emission and a lighting at the time of the echo, a flash could be very well obtained at the time of the emission and then a second flash at the time 125 of the echo, the two flashes determining on the graduated scale a sector proportional to the distance to be sounded.

130 In this case the flash of the lamp is produced by the phenomena to be observed, that

is to say either by the emission of the elastic signal or by the reception of the echo by the condenser 2. But in this case it is necessary to provide means by which, if the lamp is lighted, it will tend to be extinguished, so that only one flash of the lamp is obtained.

Fig. 4 shows by way of example an arrangement of a mechanical opening.

In general the connection between the amplifier 4 and the circuit of the relay lamp is established by any suitable means, that is to say, through autotransformers, condensers, resistances or the like. In Fig. 4 is shown a connection comprising resistances and condensers.

15 The circuit of the amplifier passes through a resistance 13 whose difference of potential, under varying conditions of operation, is impressed upon the resistance 14 through condensers 15 and 16. This resistance 14 is connected in the circuit of the lamp 17.

20 The polarizing battery is here indicated at 18 and the potentiometer at 19. A relay is likewise connected in series in the circuit of the relay lamp. Its winding 20 is shunted through condenser 21 and its armature 22 stops the current which passes through the winding. If the relay is rapid and sensitive in action the condenser 21 may be eliminated.

25 30 When there is no current flowing, the armature is urged to its closed position. The current which passes through the winding 20 when the lamp 17 is lighted is sufficient for operating the relay armature. The operation of the device is as follows:

35 The voltage of the battery 18 controlled by the potentiometer 19 is adjusted to be slightly below the upper critical voltage of lamp 17.

40 Suppose that there is no current flowing in the circuit and that armature 22 of relay 20 is in its closed position.

45 If a variation in current is produced in the resistance 13, said variation once being established either by the emission of the signal or by the echo, the variation in voltage is transmitted to the resistance 14 through condensers 15 and 16. This variation in voltage becomes added to the voltage of the battery 18 and causes a luminous discharge to be started in lamp 17. Current first of all flows through the capacity 21 and it is only after a time determined by the value of this capacity 50 and of the inductance of relay winding 20 that current is established in said winding.

55 The relay is then operated. Armature 22 opens the circuit. The lamp goes out but condenser 21 which was charged by the terminals of the winding 20 is discharged across said terminals and maintains the circuit open for a certain time. The armature 22 again makes contact, closes the circuit and the whole device is ready for receiving a new 60 over voltage.

Fig. 5 indicates, by way of example, another arrangement in which the current of the lamp instead of being arrested mechanically by itself through a relay, is arrested electrically.

In this arrangement, as a modification, the connection between the lamp circuit and that of amplifier 4 is obtained through an autotransformer 23. The battery 24 feeds through potentiometer 25, a condenser 26, through an impedance 27. The condenser 26 feeds the neon lamp 28 through the autotransformer 23. In the absence of signals to be sent the voltage of battery 24 is regulated below the upper critical voltage by the potentiometer 25.

As soon as an increase in voltage is produced in autotransformer 23 the lamp is lighted. Condenser 26 is discharged through lamp 28 and impedance 27 is sufficiently high as to not be able to maintain the discharge through lamp 28.

The voltage at the terminals of the condenser diminishes and when it reaches the lower critical value the lamp goes out.

Condenser 26 is then recharged by battery 24 through resistance 27 and at the end of a relatively short time the whole device is ready to function anew.

For more generality a neon or other lamp of lower pressure gas could be employed and which could have a plurality of electrodes interior and exterior of the tube. Fig. 6 indicates the arrangement in the case of such a lamp.

29 indicates the neon relay lamp in which there are two electrodes 30 and 31 always on the interior of the tube which may be fed through an impedance 32 by a battery 33. The voltage of this battery is regulated by a potentiometer 34 to be below the critical voltage of the lamp.

An auxiliary electrode 35, outside the lamp for example, is associated with the transformer 36 of which the primary is connected to the amplifier 4, Fig. 1. The end of this circuit is led to a potentiometer 37 connected to the battery 33.

The inventor has ascertained that a variation in voltage on the electrode 35 will bring about excitation of lamp 29 if it is extinguished and sensitized, that is, close to its upper critical point. Inversely if the lamp is sensitized close to its lower critical point extinction may be produced by acting on 35.

All of the devices disclosed in connection with the preceding figures may be employed here.

Likewise the action of a magnetic field on the discharge may be employed and the sensitizing of one or more electrodes may also be obtained by a continuous or periodic voltage.

In Fig. 7 is shown an arrangement employing the relay effect of the current of

discharge in a sounder of great depths by easily observed and indicating the phenomenon produced.

As shown in Fig. 1 here 1 represents the emitter of high frequency current operated by an ultra-audible waves projector 2. The necessary current for the transmitter 1 is furnished by a source 2' and the circuit can be opened by means of a switch 3. The echo amplifier is shown at 4.

The circuit of the neon lamp 6 is connected to the amplifier 4 by the transformer 5. The polarizing source of the lamp is at 7 and may be regulated by the potentiometer 8. The winding of a first relay 38 is placed in series in the lamp circuit with the armature of relay 9. The armature 39 of relay 38 can arrest the current furnished by the battery 40 which operates an electric timing device 41.

Suppose the lamp to be lighted by a preceding echo. The relay 9 is closed as well as the relay 39. The current of battery 40 passes through the timing device and blocks it. The needle of the timing device is then placed on the zero position.

In order to send out a signal, switch 3 is closed and as in Fig. 1, relay 9 is opened during the whole time of the emission producing the extinguishment of the lamp 6 and the stopping of relay 38. The circuit of battery 40 is opened, the electric timing device 41 is released and the needle which was primarily on the zero point is displaced at a constant speed along the graduated scale.

After the emission relay 9 closes but as the voltage of battery 7 is lower than the upper critical voltage of the lamp, the lamp does not relight and the electric timing device continues to function.

When the echo arrives it is amplified by the amplifier 4 and acts by means of transformer 5 on the neon lamp.

The connections of this transformer 5 are such that the echo gives a temporary increase of voltage and the lamp is relighted. The current which passes through the lamp operates the relay 38, the lamp circuit is closed and the timing device 41 is stopped. The needle is arrested then along the graduation and if the scale has been suitably graduated the depth sought may be read directly thereon.

In this device, as in Fig. 1 reverse operation may be obtained, that is to say, the lamp may be lighted at the emission and put out at the reception of the echo. The same slight modification employed in connection with Fig. 1^a is likewise necessary here for this reverse operation.

The form of the lamp and the electrodes may be such that the discharge takes place between two electrodes. The effect of the auxiliary electrode and the magnetic field may be arranged to vary the flash or displace the discharge, all of these phenomena being

In the present invention the arrangement of these devices in receiving apparatus for signaling by elastic waves is likewise anticipated.

What I claim is:

1. In a sounding apparatus of the type described, electrical means for transmitting and receiving elastic waves through water, a low tension glow discharge tube in said means, means for bringing this tube at a tension near the tension at which a change occurs in its lighting state, means in series with said tube and adapted to cut off and close the circuit of said tube, means to operate said last mentioned means at the time at which an electrical signal is sent out, means adapted to maintain open the circuit of the tube during the time of the emission signal, and to cause said circuit to be closed a predetermined time after the signal has been transmitted, means in series with said tube and adapted for altering the excitation thereof, means for electrically connecting said last mentioned means to the electrical means for receiving the echo signals whereby the tube is again lighted and caused to glow as long as another signal is not transmitted.

2. In a sounding apparatus of the type described, a signal transmitter for emitting waves into water, means for transforming incoming elastic waves transmitted through water into electrical oscillations, an amplifier connected to the last-mentioned means, an output circuit for said amplifier, another circuit, a low voltage glow discharge tube in the second mentioned circuit, a source of potential in said second mentioned circuit, said source being of such a voltage as to normally impress upon said tube a tension comprised between its upper critical value and its lower critical value, means operatively connected to said signal transmitter for causing the tension of said tube to suddenly take a value outside of the above mentioned limits when a signal is emitted through said transmitter, means for causing the tension of said tube to be brought back to a value within the above mentioned limits a predetermined time after the signal has been transmitted, means for coupling said output circuit of the amplifier to said circuit of the tube so arranged that the reception of an echo will produce a variation of the voltage of said tube to a value outside of the above mentioned limits but in a direction opposed to that of the variation resulting from the emission of a signal, and means for recording the interval of time between the variations in the luminous state of the tube.

3. In a sounding apparatus of the type described, a signal transmitting for emitting elastic waves into water, means for transforming incoming elastic waves transmitted

- through water into electrical oscillations, an amplifier connected to the last mentioned means, an output circuit for said amplifier, another circuit, a low voltage glow discharge tube in the second mentioned circuit, a source of potential in said second mentioned circuit, said source being of such a voltage as to normally impress upon said tube a tension comprised between its upper critical voltage and 5 its lower critical voltage, a switch for operating said transmitter, means operatively connected to said transmitter switch for causing the tension of said tube to suddenly take a value outside of the above mentioned limits when a signal is emitted through said transmitter, means for causing the tension of said tube to be brought back to a value within the above mentioned limits a predetermined time after the signal has been sent out, means for 10 coupling said output circuit of the amplifier to said circuit of the tube so arranged that the reception of the echo will produce the variation of voltage of said tube to a value outside of the above mentioned limits but in a direction opposed to that of the variation 15 resulting from the emission of a signal, and means for recording the interval of time between the variations in the luminous state of the tube.
4. In a sounding apparatus of the type described, a signal transmitter for emitting elastic waves into water, means for transforming incoming elastic waves transmitted through water into electrical oscillations, an 20 amplifier connected to the last mentioned means, an output circuit for said amplifier, another circuit, a low voltage glow discharge tube in the second mentioned circuit, a source of potential in said second mentioned circuit, 25 said source being of such a voltage as to normally impress upon said tube a tension very slightly lower than the upper critical voltage of said tube, a switch for operating said transmitter, a relay in series with said switch and adapted to break and make the circuit of said tube a source of current, and a condenser in series with said switch and said relay for causing said relay to suddenly break the circuit of said tube when a signal is emitted through said transmitter, said transmitter being so chosen as to cause said 30 relay to return to its initial position a predetermined time after the signal is sent out, whereby the tension impressed upon said tube is brought back to its initial value, means for coupling said output circuit of the 35 amplifier to said circuit of the tube so arranged that the reception of the echo will produce a variation of the voltage off said tube to a value outside of the above mentioned limits but in a direction opposed to that of the variation resulting from the emission of a signal, and means for recording the 40 interval of time between the variations in the luminous state of the tube.
5. In a sounding apparatus of the type described, a signal transmitter for emitting elastic waves into water, means for transforming incoming elastic waves transmitted through water into electrical oscillations, an amplifier connected to the last mentioned means, an output circuit for said amplifier, another circuit, a low voltage glow discharge tube in the second mentioned circuit, a source of potential in said second mentioned circuit, 45 said source being of such a voltage as to normally impress upon said tube a tension comprised between its upper critical voltage and its lower critical voltage, a switch for operating said transmitter, a relay in series with said transmitter switch and adapted to break and make the circuit of said tube a source of current and a condenser in series with said switch and said relay for causing said relay to suddenly operate in such 50 manner as to cause the tension of said tube to suddenly take a value outside of the above mentioned limits when a signal is emitted through said transmitter, said condenser being so chosen as to cause said relay to return to its initial position a predetermined time after a signal is sent out, whereby the tension of said tube is brought back to a value within the above mentioned limits, means for coupling said output circuit of the amplifier to 55 said circuit of the tube so arranged that the reception of the echo will produce a variation of the voltage of said tube to a value outside of the above mentioned limits but in a direction opposed to that of the variation resulting from the emission of a signal, and 60 said source being of such voltage as to normally impress upon said tube a tension very slightly higher than the lower critical voltage of said tube, an auxiliary source of potential, a switch for operating said transmitter, a relay in series with said switch and adapted to insert said auxiliary source of potential in said circuit of the tube or to remove it therefrom, a source of current and a condenser in series with said switch and said relay for causing said relay to suddenly insert said auxiliary source of potential in said circuit of the tube when a signal is emitted through said transmitter, said condenser being so chosen as to cause said relay to return to its initial position a predetermined time after 65

the signal is sent out, whereby the tension of said tube is brought back to its initial value, means for coupling said output circuit of the amplifier to said circuit of the tube so arranged that the reception of the echo will produce a variation of the voltage of said tube to a value outside of the above mentioned limits but in a direction opposed to that of the variation resulting from the emission of a signal, and means for recording the interval of time between the variations in the luminous state of the tube.

7. In a sounding apparatus of the type described, a signal transmitter for emitting elastic waves into water, means for transforming incoming elastic waves transmitted through water into electrical oscillations, an amplifier connected to the last mentioned means, an output circuit for said amplifier, another circuit, a low voltage glow discharge tube in the second mentioned circuit, a source of potential in said second mentioned circuit, said source being of such voltage as to normally impress upon said tube a tension comprised between its upper critical voltage and its lower critical voltage, means operatively connected to said signal transmitter for causing the tension of said tube to suddenly take a value outside of the above mentioned limits when a signal is emitted through said transmitter, means for causing the tension of said tube to be brought back to a value within the above mentioned limits a predetermined time after the signal has been sent out, means for coupling said output circuit of the amplifier to said circuit of the tube so arranged that the reception of the echo will produce a variation of the voltage of said tube to a value outside of the above mentioned limits in the same direction as that of the variation resulting from the emission of a signal, means for causing the tension of said tube to be brought back to a value within the above mentioned limits a predetermined time after the echo has been received, and means for recording the interval of time between the variations in the luminous state of the tube.

8. In a sounding apparatus of the type described, electrical means for transmitting and receiving elastic waves through water, a stationary glow discharge tube in said means, means for bringing the tube at a tension near the tension at which a change occurs in its lighting state, means in series with said tube and adapted to cut off and close the circuit of said tube, means to operate said last mentioned means at the time at which an electric signal is sent out, means adapted to maintain open the circuit of the tube during the time of the emission signal and to cause said circuit to be closed a predetermined time after the signal has been transmitted, means in series with said tube and adapted for altering the excitation thereof, means for electrically connecting said last

mentioned means to the electrical means for receiving the signal echo, whereby the tube is again lighted and caused to glow as long as another signal is not transmitted, a stationary scale and rotary reflecting means adapted to revolve around said tube for directing upon said scale a movable image of said tube.

In testimony whereof I have signed this specification.
